MACHINE FOR APPLYING FOLDED STRIP

Albert J. Germain and Andrew J. Germain,
Haverhill, Mass.

Application September 4, 1941, Serial No. 409,560

13 Claims.

(Cl. 12—17)

This invention relates to the folding longitudinally of a strip of sheet material and the securing of the strip thus folded to a blank, and as here illustrated is arranged to apply this folded strip to the marginal portion of a shoe sole blank in the manufacture of a shoe innersole. In order to apply the strip in position it is coated on one face with an adhesive.

One of the objects of this invention is to accomplish the automatic feeding and folding of this strip in such a manner that the adhesively coated face has little contact with any of the machine parts thus to prevent removal of the adhesive from the strip and the gumming up of machine parts with such adhesive.

A further object is to provide a strip feed which is automatically adjustable in accordance with the requirements of the work to avoid, on the one hand, the placing of undue tension on the strip where it is applied to the work, and on the other hand, an undue slackness between the source of supply and the point of application to the work.

Further objects and advantages will appear from a more complete description of an embodiment of this invention shown in the accompanying drawings in which

Figures 1 and 2 are side elevation and top plan views, respectively, of a machine embodying the invention.

Figure 3 is a detail sectional view to a larger scale on line 3—3 of Figure 1.

Figure 4 is a detail sectional view on line 4—4 of Figure 3.

Figure 5 is a detail section to a larger scale on line 5—5 of Figure 2.

Figure 6 is a perspective view of an innersole blank having the folded strip applied thereto around the forepart.

Figure 7 is a lateral sectional view through the forepart of the innersole of which the product shown in Figure 6 is a part, the right hand edge portion being shown in condition to receive inseam stitching.

Figure 8 is a fragmentary perspective view showing the folder and related parts.

The machine as shown in Figures 1 and 2 comprises a base 1 which may be supported on a table or bench and from the rear end of which extends upwardly a standard 2 having an arm 3 at its upper end extending forwardly from the arm 2 and over the forward portion of the base 1. This arm 3 has at its forward end a pair of vertically spaced sleeves 4 within which is slidably mounted a rod 5 to the lower end of

which is secured an arm 6, on which is rotatably mounted a frusto-conical presser roller 7 which is shown as having a knurled periphery. The bar 5 is normally downwardly pressed as by a spring 8 reacting between the under face of the upper sleeve 4 and a collar 9 pinned to the rod 5, thus to hold the roller 7 downwardly pressed toward a supporting and feed roller 10 projecting upwardly through a slot in the base 1 and carried by a shaft 12 journaled beneath the top face of the base 1. This roller 10 is arranged to be rotated to feed the work and to this end the shaft 12 is shown as provided beneath the post 2 with a worm wheel 13 meshing with a worm 14 on a vertical shaft 15 rotatably supported in the standard 2. At its upper end this shaft 15 carries a bevel gear 16 meshing with a bevel gear 17 on a horizontal drive shaft 18. This drive shaft carries a pulley 20 on its outer end or any other suitable means by which it may be rotated. When using a pulley, the rotation may be effected through a drive belt 21 from any suitable driving means.

It will be seen that the feed roller 10 revolves by power, but that the presser roller 7 is journaled with free rotary motion, being rotated by the motion of work with which it contacts and which is fed by rotation of the feed roller 10. The bar 5 may be lifted to permit the ready insertion or removal of work between the rollers 7 and 10 and to this end, the collar 9 may be provided with a transverse pin 23 beneath which may engage one arm 24 of a lifter lever 25 pivoted at 26 to the machine arm 3.

Supported in any suitable way adjacent to the machine is a reel 30 which may carry a supply of the strip material which is to be folded and applied to a blank fed between the rollers 10 and 7. As shown this reel comprises a disk on which a roll of the strip material, as 31, may be supported. This disk as shown is carried at the outer end of the arm 32 extending from the base 1. A spring coil 33 fixed to a central pin 34 of the supporting arm 32 may be employed to resiliently engage the inner face of a coil of the strip material 31, thus to hold this coil in feeding position. This strip material is provided with an adhesive on one face and its opposite face is so formed as to not adhere strongly to the adhesive. As is well known in the art this may be done by applying a coating of wax or other material to which the adhesive cannot strongly adhere to the face of the strip opposite to the adhesively coated face.

The strip leads off from the supply and to a

feeding means by which it is conducted to a folder, which may be of a conventional form, located at 35 (see Figures 1, 2 and 8). This feeding mechanism as shown consists of three feeding mechanisms. The one nearest to the folder comprises a continuously moving endless surface element shown as a feed roller 40 fixed to the shaft 12 to be rotated therewith. The strip material *a* passes around a considerable extent of the periphery of this roller 40 and passes therefrom over a flanged pulley 41 and about a second flanged pulley 42 at right angles thereto to the folder 35 wherein the strip material is folded with its non-sticky face inwardly presented. This folder is positioned closely adjacent to the nip between the rollers 7 and 10 so as to permit the roller 7 to engage on the upper face of the folded strip and press it against the marginal portion of a blank 45, the marginal portion of which rides on the feed roller 10 in the position shown in Figure 5. The strip *a* is presented to the upper face of the blank 45 herein shown as an innersole blank and in full view of the machine operator, the roller 7 pressing the folded strip against the blank with the fold line of the strip positioned inwardly from the outer margin of the blank while the free edges of the fold are in substantial registry with the blank edge, these parts being held in proper relation to the edge of the feed roller 7 by an edge gage member 46. Both the edge gage member 46 and the folder 35 are shown as carried by bars 47 and 48 having adjustable screw and slot connections through the base 1 which permits them to be adjusted to the proper positions relative to the edge of the sole member.

Between the continuously rotatable feed roller 40 and the supply 31 are a pair of feed mechanisms, the first one being arranged to take the tape from the source and feed it toward the roller 10, while the other feed mechanism is an automatically acting mechanism which supplements the first feeding mechanism as may be required to produce a feed of the strip toward the feed wheel exactly in accordance with the requirements of the work. As shown both of these feed mechanisms which take from the supply are intermittent in their action. The one nearest to the supply, as shown best in Figures 2 and 4, consists of an angle-shaped member 50 having a slot 51 through the long leg of the angle member and adjacent to the inner face of the short leg 52. To the long leg 53 is secured as by a screw 54, one end portion of a leaf spring 55, the opposite end of which bears against the strip on its adhesive coated face and acts as a pawl to prevent retracting motion of the strip relative to the feed member 50. This member 50 is secured to an end of a bar 56 as by a screw 57, and this bar 56 has one end portion cut away as at 58 to form a recess within which is journaled a cam roller 59 on a stub shaft 60. This cam roller bears against the outer face of an eccentric 61 secured to the shaft 18 so that as the shaft 18 is rotated, the cam follower 59 is caused to reciprocate and with it the bar 56, in a direction axially of this bar. The cam roller 59 is held up against the periphery of the eccentric 61 as by a coil spring 65 reacting at one end against a collar 66 pinned to the bar 56 and at the other end against the base of a casing member 67 through which the bar 56 reciprocates. This casing 67 may be secured to a bracket member 68 secured to the inner face of the standard 2. As this bar 56 is reciprocated, it moves the feed ele-

ment 50 in a similar manner, the spring 55 engaging the strip as the feeder 50 moves from the full line position to the dotted line position of Figure 4, carrying the strip with it and peeling it off from the supply, the spring 55 preventing the feeder 50 from sliding idly over the strip. This reciprocating feed mechanism is so proportioned as to feed the strip material very nearly as fast as it can be taken by the continuously rotatable feed roller 40, it being of course evident that because of the intermittent nature of this feed member 50, at each feeding stroke it pulls off an excess of strip material which is gradually taken up by the feed roller 40 during the idle time when the element 50 is being retracted, at which time the member 50 slides idly over the strip. At this time, however, the strip is held against retracting motion by means comprising a flanged guide roller 70 over which the strip *a* passes, where it is engaged by the free end of a leaf spring 71 adjustably fixed to a screw tightened slide 72 which is mounted for longitudinal adjustment on a guide piece 73 secured as by screws 74 to a suitable portion of the machine frame. The engagement of the free end of the spring 71 on the adhesive coated side of the strip prevents retrograde motion of the strip on backward movement of the feed member 50 but it is yieldable to permit the strip to pass in the opposite direction toward the periphery of the feed roller 40. In order to prevent the strip from sticking to the feed mechanism, it is arranged with its non-sticky side against the inner face of the feed member 50 and around the pulley 70 and around the feed roller 40, as shown this requiring the strip to be twisted somewhat between these members which engage it, since their feeding surfaces are movable in different planes.

It will be noted that the shaft 12 which carries the feed roller 40 is positioned out of vertical alignment with the pulley 70 so that there is an unsupported stretch of the strip material between the pulley 70 and the feed roller 40, which may at times be slack because of the relatively fast intermittent feed of the strip by the feed member 50 and the slower but continuous feed motion of the strip from the feed roller 40.

It is, of course, important that the strip be fed at a speed to meet the requirements of the work feed roller 10 so as to avoid undue tension on the strip which might cause breakage and would be liable to cause puckering or other improper laying of the strip on the face of the sole member. It is also important that the strip be fed at a rate not too fast, which would result in undue slackness of the strip material. Both of these factors are of particular importance since their effects are cumulative if they are allowed to continue. There is also some variation in the requirements of the strip feed when the strip is applied to portions of different curvature on the sole member due to unavoidable slippage between the feed wheel 10 and the blank, which further complicates the feed requirements. In order to automatically provide for the proper feed regardless of variations therein due to slippage or other cause, a supplemental feed mechanism has been devised which feeds an amount determined automatically by the degree of slackness or tightness of the strip material in the length between the feed wheel 40 and the pulley 70. This mechanism as shown is intermittently actuated and cooperates with the unsupported stretch of the strip material be-

tween the pulley 70 and the feed wheel 40. As shown it is driven by the same means which actuates the feed element 50. It comprises a rod 76 secured at its rear end to a suitable part of the intermittent feed actuator and as shown to the stub shaft 60 to which it is adjustably secured as by a set screw 77 (see Figure 4). The opposite end portion of the rod 72 is turned to form a pusher portion 78 so positioned that it may at times engage the unsupported stretch of the strip material between the pulley 70 and the feed wheel 40.

As the feed member 50 is moved in feeding direction, the supplemental corrective feed member 76 is likewise moved, bringing its pusher portion 78 toward the strip material in the unsupported stretch, thus pushing the strip material past the pulley 70 and taking up the feed produced by the motion of the feeder element 50. Due to the angularity of the engagement of the feed rod 76 to the length of the strip the amount of feed effected by an extent of motion of this rod after it engages the strip and equal to the corresponding motion of the member 50 in line with the strip produces a greater amount of feed than the motion of the element 50, thus pulling an additional length of strip material through the element 50 from the supply. The extent of this additional pull is dependent on the time in the feed stroke that the feed rod engages the strip which in turn is dependent on the amount of slack in the unsupported stretch. If it engages the strip early, it acts to pull off a greater amount with the help of the feeder 50, then if it engages this stretch later, so that the amount pulled off at each stroke by these two intermittent feed mechanisms is measured by the requirements of the feed roller 40 since its previous feed. Thus the amount pulled off from the supply is automatically regulated in accordance with the requirements of the continuously moved feed surface of the feed wheel 40. After passing the feed wheel 40, it passes over the guide pulleys 41 and is directed to the folder 35 and then to the work as previously explained. It will be noted, also, that the strip material engages with its non-adhesive face about these pulleys and is guided by the pulley 42 with its non-adhesive coated face against a wall of the folder 35, so that the internal surface of the folder has minimum contact with the adhesive.

The strip emerges from the folder in folded condition as shown best in Figure 8 and with the adhesive coated face outwardly presented, the non-adhesive face being on the inside of the fold. The strip is thus in condition to be secured to the upper face of the sole blank 45 to adhere thereto, the knurled presser wheel 7 causing it to make close contact and its knurled surface acting to remove a minimum of the adhesive from the upper face of the strip.

Where this machine is employed to apply the folded strip in this manner to the marginal portion of one face of a sole blank, it may do so about the forepart of the blank only, as shown in Figure 6, or it may be carried around through the shank portion or around the shank and heel, if desired, depending upon the manner in which the shank and heel of the shoe is to be lasted. To whatever portion of the sole blank it is applied, however, it is intended to receive thereover a reinforcing layer of fabric such, for example, as duck or canvas as shown at 80 in Figure 7. The top adhesive coated portion of the strip adheres to the lower face of the fabric

layer 80 so that when the marginal portion of this fabric layer is turned inwardly from the position shown on the left hand side of Figure 7 to the position shown on the right hand side, it is in position to form an inseam stitch-receiving rib spaced from the margin of the inner-sole by the distance of the line of fold at 81 from the outer margin of the innersole. This inner-sole per se forms no part of our invention.

From the foregoing description of an embodiment of this invention, it should be evident to those skilled in the art that various modifications and changes might be made without departing from the spirit or scope of this invention.

We claim:

1. In combination, means for supporting and feeding continuously the marginal portion of a work blank, means for feeding a strip of sheet material having an adhesive surface, means for folding said strip longitudinally with the adhesive surface outwardly presented, and means for directing the strip so folded against the face of the blank adjacent to said feeding means and for pressing said strip against said blank.

2. In combination, means for supporting and feeding continuously the marginal portion of a sole blank, means for feeding a strip of sheet material having an adhesive surface, means for folding said strip longitudinally with the adhesive surface outwardly presented, and means for directing the strip so folded against the face of said sole blank adjacent to said feeding means and with the folded edge positioned inwardly from the edge of said blank and for pressing said strip against said blank.

3. In combination, means for supporting and feeding continuously the marginal portion of a work blank, means for feeding a strip of sheet material having an adhesive surface, means for folding said strip longitudinally with the adhesive surface outwardly presented, and means for directing the strip so folded against the face of the blank adjacent to said feeding means and for pressing said strip against said blank, said feeding means including mechanism responsive to the speed of application of said strip to said blank for regulating the rate of feed of said strip to said folding means.

4. In combination, means for supporting and feeding continuously the marginal portion of a work blank, means for feeding a strip of sheet material having an adhesive surface, means for folding said strip longitudinally with the adhesive surface outwardly presented, and means for directing the strip so folded against the face of the blank adjacent to said feeding means and for pressing said strip against said blank, said feeding means including an intermittently acting feed element mounted to engage an unsupported stretch of the strip and to feed said strip by an amount dependent upon the tightness or slackness of said stretch.

5. In a machine of the class described, a strip feeding means comprising a continuously moving endless surface member, means in advance of said endless surface member for pulling off said strip material from a supply, there being an unsupported stretch of the strip between said pulling off means and said endless surface member, and a reciprocatory feeding member actuatable to engage the strip on its upper face at said stretch and depress said strip and draw the strip through said pulling off means to an extent depending on the amount of slack in said stretch.

6. In a machine of the class described, a strip-feeding means comprising a continuous feeding mechanism and a pair of intermittent feeding mechanisms arranged in series and feeding to said continuous feeding mechanism, means for actuating said intermittent mechanisms in unison, the second of said intermittent feeding mechanisms having an intermittent effective feeding stroke determined by the amount by which said first intermittent feeding mechanism feed is less than the feed requirement of said continuous feeding mechanism and acting when effective to pull the strip through said first intermittent feeding mechanism.

7. In a machine of the class described, a strip feeding means comprising a continuous strip feeding mechanism and an intermittent strip feeding mechanism delivering the strip material to said continuous feeding mechanism, and a supplemental feeding mechanism between said continuous and intermittent feeding mechanism having an effective feeding action dependent on the amount of slack in said strip between said continuous and intermittent feeding mechanisms.

8. In a machine of the class described, a strip feeding means comprising a pair of feeding mechanisms spaced along the strip, and a supplemental feeding mechanism between said spaced mechanisms and having an effective feeding action dependent on the difference of effective feeding speeds of said spaced mechanisms.

9. In a machine of the class described, a strip feeding means comprising a pair of feeding mechanisms spaced along the strip, a supplemental feeding mechanism between said spaced mechanisms and having an effective feeding action dependent on the differences of effective feeding speeds of said spaced mechanisms, and means for intermittently actuating said supplemental feeding mechanism.

10. In combination, means for supporting and feeding the marginal portion of a work blank, means for feeding a strip of sheet material hav-

ing an adhesive surface, means for folding said strip longitudinally with the adhesive surface outwardly presented, and means for directing the strip so folded against the face of the blank adjacent to said feeding means and for pressing said strip against said blank.

11. In combination, means for supporting and feeding the marginal portion of a sole blank, means for feeding a strip of sheet material having an adhesive surface, means for folding said strip longitudinally with the adhesive surface outwardly presented, and means for directing the strip so folded against the face of the sole blank adjacent to said feeding means and with the folded edge positioned inwardly from the edge of said blank and for pressing said strip against said blank.

12. In combination, means for supporting and feeding the marginal portion of a work blank, means for feeding a strip of sheet material having an adhesive surface, means for folding said strip longitudinally with the adhesive surface outwardly presented, and means for directing the strip so folded against the face of the blank adjacent to said feeding means and for pressing said strip against said blank, said feeding means including mechanism responsive to the speed of application of said strip to said blank for regulating the rate of feed of said strip to said folding means.

13. In a machine of the class described, a strip feeding means comprising a driven endless surface member, means in advance of said endless surface member for pulling off said strip material from a supply, there being an unsupported stretch of the strip between said pulling off means and said endless surface member, and a feeding member reciprocally movable to engage the strip on its upper face at said stretch and depress said strip and draw the strip through said pulling off means to an extent depending on the amount of slack in said stretch.

ALBERT J. GERMAIN.
ANDREW J. GERMAIN.
